CHASSIS MOUNTING FOR RADIO RECEIVERS
AND THE LIKEWilliam J. Snyder, Brookline, Pa., assignor to
Philco Radio & Television Corporation, Philadelphia, Pa., a corporation of Delaware

Application March 11, 1935, Serial No. 10,528

5 Claims. (Cl. 248—358)

This invention relates to a novel mounting for a radio chassis or the like and has for its principal object the provision of an improved mounting for the receiver chassis within the usual cabinet of the radio receiver.

Another object of the invention is to provide a radio receiver chassis mounting which is simple and which facilitates assembly of the chassis within the cabinet and which requires little or no attention or manipulation by the customer.

A further object of the invention is to provide a mounting which is adapted to floatingly support the chassis and which prevents displacement of or injury to the parts of the radio receiver, particularly during shipping thereof.

Still another object of the invention is to provide a mounting which serves to align certain parts of the radio receiver, thereby insuring that the parts may be readily assembled without difficulty.

The invention may be clearly understood by reference to the accompanying drawing illustrating a preferred embodiment.

In the drawing:

Fig. 1 is a fragmentary section taken through the radio receiver cabinet and showing the receiver chassis and the mounting therefor in side elevation;

Fig. 2 is a perspective view of the receiver chassis turned up on its rear wall;

Fig. 3 is an enlarged fragmentary section taken through one of the front mounting units;

Fig. 4 is a similar view of one of the rear mounting units;

Fig. 5 is a perspective view of one of the mounting elements;

Fig. 6 is a face view of the same;

Fig. 7 is a perspective view showing certain parts of another of the mounting units; and

Fig. 8 is a perspective view of the sleeve which is adapted for association therewith.

Referring to Fig. 1, the numeral 1 designates the front wall of the usual radio receiver cabinet, while the numeral 2 designates the horizontal shelf or bottom wall of the cabinet upon which the radio receiver is mounted. The receiver chassis is shown at 3 and in accordance with the present invention, the chassis is mounted within the cabinet by means of a pair of front mounting units 4 and a pair of rear mounting units 5. The chassis may take the form of an inverted shallow box, as shown in Fig. 2, to accommodate the terminals and wiring or other elements as in usual practice. It will be understood that the essential parts of the receiver, such as the trans-

formers, tuning condensers, vacuum tubes, etc., will be mounted on top of the chassis as is the custom.

In the present instance, the front wall of the chassis is provided with integral projections or lugs 6 which are spaced apart near the top of the chassis, as shown clearly in Fig. 2. As illustrated in Fig. 3, these lugs may be formed by extruding small sheet metal disks and inserting the members thus formed through openings in chassis wall and spot welding the said members to the wall. Near the rear wall of the chassis, there are provided spaced mounting portions 7 which may be provided with tapped holes or apertures 8. Thus, there are established four mounting points 10 for the chassis and the elements just described are adapted to cooperate with the mounting units in the manner now to be described.

In Fig. 3, there is shown one of the front mounting units 4 which comprises a recessed or cup-like member 9 formed of highly resilient material, such as live rubber. As shown more clearly in Figs. 5 and 6, this member has a cylindrical portion 10 with a deep cylindrical recess 11 extending axially thereof but eccentrically located as shown in Fig. 6. An integral bead or ridge 12 is provided along the bottom of the cylindrical portion 10. At one end of the cylindrical portion, there is provided a flange or head 13.

The front wall 1 of the cabinet is provided with recesses 14 of such size and shape as to snugly receive the body portion of the resilient member 9 with the flange 13 abutting against the rear surface of wall 1. When positioned in the wall recesses, the resilient members 9 are adapted to snugly receive the lugs 6 with the front wall of the chassis abutting against the flanges or heads 13, as shown clearly in Fig. 3. It will be seen that this provides a resilient mounting for the front of the chassis, substantially preventing movement of the chassis in any direction parallel to the cabinet wall 1 and effectively cushioning the front portion of the chassis and maintaining it free of contact with the receiver cabinet. It will now be apparent that the reason for having the recesses 11 of the members 9 eccentrically located and for providing the beads or ridges 12 is to give an increased thickness of the resilient member beneath lugs 6 where it is most needed and to key the eccentric recesses 11 in proper positions. This latter function is effectively performed by the beads or ridges. It will also be seen that the front mounting units serve to locate properly the front wall of the chassis with respect to the cabinet wall 1 so that the parts 55

of the receiver, such as the tuning control extending through the wall, are correctly aligned with the cabinet wall, thus preventing binding of said controls. The mounting further serves to prevent damage to these parts in shipment.

In Fig. 4, there is shown one of the rear mounting units 5. Each of these units comprises a sleeve or bushing 15 (see Fig. 7) having an enlarged head or flange 16 and which is adapted to seat in an opening 17 in the bottom wall 2 of the radio cabinet with the head or flange 16 resting against the upper surface of the wall 2. This sleeve or bushing is also formed of highly resilient material such as live rubber. The unit also comprises a washer 18 formed of similar material, a metallic washer 19, and a metallic sleeve 20.

These elements are assembled as shown clearly in Fig. 4. The sleeve 20 is positioned within the sleeve or bushing 15, while the resilient washer 18 abuts against sleeve 15. The metal washer 19 is placed against the resilient washer and abuts the lower end of sleeve 20. The mounting portion 7 of the chassis seats upon the head or flange 16 and a screw 21 passes through the assembled elements and serves to fasten the chassis.

Thus, there are provided at the rear of the chassis two cushioning mounting units which serve to floatingly support the rear portion of the chassis and to prevent movement thereof parallel to wall 2. The sleeve 20 serves as a spacer and limits the compression of the resilient members to the desired degree when the screw 21 is tightened. The metal washer serves as a pressure member, applying pressure caused by tightening of the screw over the area of the resilient washer 18.

It is important to note that the chassis is resiliently or floatingly supported at four points arranged in pairs which are diagonally located. This not only facilitates assembly but is also more effective in the provision of a full-floating chassis than would be the case if the mounting units were located otherwise. In assembly, it is merely necessary to position the chassis within the cabinet with the lugs 6 in their recessed cushioning elements and the rear portion of the chassis will then be in proper position upon the cushioning sleeves or bushings 15 to enable rapid and easy attachment. With the chassis thus mounted, it is effectively shielded against jolts, such as might be caused by contact with the rigid cabinet during shipping. The delicate parts of the receiver carried by the chassis are, therefore, protected against injury. Furthermore, the mounting requires no attention or manipulation on the part of the customer when the assembled radio receiver reaches him. A still further advantage of the mounting is that it completely isolates the chassis from the radio cabinet, thereby preventing transmission of vibrations from the cabinet through the chassis to be responsive elements of the receiver. Such vibrations are prone to cause microphonic action of the said elements. This is effectively prevented by the isolation of the chassis from the cabinet.

It has been the practice heretofore to mount the receiver chassis upon four supports and to provide one or more cushioning elements between the front wall of the chassis and the front wall of the cabinet. The present invention eliminates the necessity of such cushioning elements, since the front mounting units serve this

purpose. Moreover, only two bottom supports are necessary in the present mounting, the front mounting units serving to support the front portion of the chassis. A still further advantage of the invention is that the construction of the mounting units eliminates the necessity of attention or manipulation by the customer which has been required by prior devices. 5

It will be understood, of course, that the invention is susceptible to modification or change such as will occur to persons skilled in the art and, therefore, it is to be limited only by the scope of the appended claims.

I claim:

1. A mounting for a radio set chassis and the like, comprising a pair of mounting units seating the bottom of the chassis near the rear thereof, and a second pair of mounting units seating the front of the chassis, said first pair of units each comprising a resilient flanged sleeve or bushing seated in an opening in a bottom wall of the radio cabinet and resiliently supporting the chassis on its flanged end, a resilient washer at the opposite end of said sleeve, an attachment element extending through the chassis and through the sleeve and washer, and a rigid sleeve within said resilient sleeve, and said second pair of units each comprising a flanged cup-shaped resilient member seated in a recess in the front wall of the cabinet with its flanged portion engaged by the chassis and adapted to receive a projection on the chassis, whereby the chassis is floatingly mounted.

2. In a radio set having a cabinet and a chassis, means for resiliently supporting the chassis comprising a resilient generally cylindrical member having a flanged end and having a cylindrical aperture extending inward from said flanged end and disposed eccentrically above the axis of said member, said member being seated snugly in a recess in a wall of said cabinet with its flange against a face of said wall, and a cylindrical projection on said chassis seated in the aperture of said resilient member with a face of said chassis engaging said flange. 45

3. In a radio receiver, a front supporting wall, a radio receiver chassis having a front wall in proximity to said supporting wall, chassis supporting means comprising a plurality of resilient recessed members at the upper front part of said chassis each having a flanged end and seated in a recess in one of said walls with its flange bearing thereagainst, projections on the other of said walls seated in the recesses of said resilient members, said flanges being of substantial area to serve as cushion rests for said other wall, and means for resiliently supporting and anchoring the rear lower part of said chassis and permitting only limited movement of the chassis insufficient to enable said projections to withdraw from said recessed members, the aforesaid diagonally located supporting means being the only supports for said chassis, whereby said chassis may be mounted by first inserting said projections in said recessed members and then securing said rear supporting means, and said chassis when mounted is floatingly supported but is positively prevented from moving forwardly or laterally in an amount sufficient to deleteriously affect the delicate radio parts. 50

4. In a radio receiver, a front supporting wall, a horizontal supporting panel, a radio receiver chassis having a front wall in proximity to said supporting wall and having a bottom in proximity to said panel, chassis supporting means compris- 70 75

ing a plurality of resilient recessed members each having a flanged end and seated in a recess in one of said walls with its flange bearing thereagainst, projections on the other of said walls seated in the recesses of said resilient members, said flanges being of substantial area to serve as cushion rests for said other wall, and means attached to said panel for resiliently supporting and anchoring the rear of said chassis and permitting only limited movement of the chassis insufficient to enable said projections to withdraw from said recessed members, the aforesaid supporting means being the only supports for said chassis, whereby said chassis may be mounted by first inserting said projections in said recessed members and then securing said rear supporting means, and said chassis when mounted is floatingly supported but is positively prevented from moving forwardly or laterally in an amount sufficient to deleteriously affect the delicate radio parts.

5. In a radio receiver, a front supporting wall, a horizontal supporting panel, a radio receiver chassis having a front wall in proximity to said supporting wall and having a bottom in proximity

to said panel, chassis supporting means comprising a plurality of resilient recessed members each having a flanged end and seated in a recess in said supporting wall adjacent the upper part of said chassis wall with the flange of said member bearing against said supporting wall, a projection on the upper part of said chassis wall seated in the recesses of said resilient members, said flanges being of substantial area to serve as cushion rests for said chassis wall, and means attached to 10 said panel for resiliently supporting and anchoring the rear lower part of said chassis and permitting only limited movement of the chassis insufficient to enable said projections to withdraw from said recessed members, the said diagonally located supporting means being the only supports for said chassis, whereby said chassis may be mounted by first inserting said projections in said recessed members and then securing said rear supporting means, and said chassis 15 when mounted is floatingly supported but is positively prevented from moving forwardly or laterally in an amount sufficient to deleteriously affect the delicate radio parts.
